METHOD OF DRIVING STAPLES

Desmond R. La Place, Pittsburgh, Pa., assignor
to Bocil Corporation, a corporation of Delaware

Application September 3, 1942, Serial No. 457,166

8 Claims. (Cl. 1—49)

This invention pertains to the art of stapling and is a continuation-in-part of my copending applications Serial No. 386,497, filed April 2, 1941 for improvements in Fasteners and method of fastening and Serial No. 386,498, filed April 2, 1941 for Stapling hammer. The invention is also related to my copending application Serial No. 457,165, filed September 3, 1942 for Method and apparatus for stapling.

In the first of the foregoing applications there is disclosed a staple having a top portion which is connected to substantially parallel leg portions through relatively small extensions forming connections between the legs and the head. The head and the legs are normally in substantially a plane so that the fasteners may be arranged in rows in face to face relation. Moreover, the fasteners are shaped so that the rows may be arranged when desired in point to back relation with the head portions of the staples of one row extending up between the legs of the staples of the row above. These staples are designed to be driven by effecting relative rotation between the head portion and the leg portion of each staple until the head portion is at substantially right angles to the legs. The head then presents a relatively large surface to the underlying material and such staple is intended to replace large headed nails or tacks such as those used for securing roofing or sheathing paper to a wooden structure or such as the tacks used for securing upholstery to a wooden frame. I refer to such staples as "tilt-top" staples.

In the second application above referred to, I have disclosed a driving tool in the form of a hammer for driving staples of this type. In the specific form of hammer illustrated the staples are delivered one at a time to the guide of the stapling tool. They are engaged by a driver which simultaneously starts to drive the staple and rotate the head relatively to the legs. Before the staple has been completely driven the rotation of the head has been completed and in the final operation the head of the staple lies flat against the surface into which the staple has been driven. In the third application above referred to the head of the staple is confined in a plane while the legs are turned relatively to the head. This is accomplished as a step in the driving operation but the movement of the legs of course occurs before the points of the legs have penetrated the surface into which they are to be driven. The said application is specific to that particular method and to a driving tool for accomplishing that method.

The present application is directed generically to the method of stapling wherein relative rotation is effected between the head and the legs of the staple to turn the head from the plane of the legs to a plane substantially perpendicular to the legs. It is directed specifically to the method which comprises rotating or tilting the head relatively to the legs and more especially to the method of accomplishing the turning of the head and the driving of the staple in a single stroke of the driver.

The invention may be more fully understood by reference to the accompanying drawing, in which:

15 Figure 1 is a front elevation more or less schematically showing a stapling tool with the staple in place therein in position to be driven, part of the tool being shown in section;

20 Figure 2 is a transverse vertical section through Figure 1, the staple, however, being shown in elevation;

25 Figure 3 is a transverse horizontal section in substantially the plane of line III—III of Figure 1, the top plan elevation of the staple being shown;

Figure 4 is a view similar to Figure 1 showing the beginning of the driving of the staple;

Figure 5 is a view similar to Figure 2 showing the beginning of the driving of the staple;

30 Figure 6 is a view similar to Figure 5 showing a further step in the driving of the staple in which the head of the staple has been turned;

Figure 7 is a view similar to Figure 4 but showing the completion of the driving stroke;

35 Figure 8 is a top plan view of the staple after it has been driven;

Figure 9 is a view similar to Figure 1 in which the staple is illustrated as being formed of wire; and

40 Figure 10 is a view similar to Figure 5 showing a step in the driving of a wire staple.

Referring first to Figures 1 to 8, inclusive, the staple or fastener designated generally as 2 has substantially parallel legs 3 and a disk-like top 4 which is narrower than the distance between the legs. The top or head of the staple 4 is connected with legs through lateral extensions 5. The head and the legs, as clearly shown in Figure 2, are substantially in a plane.

45 The driving tool, designated generally as 6, comprises a guide having parallel side members 7 in which reciprocates a driver 8. The inner faces of the guides 7 are provided with grooves or channels 9 as best shown in Figures 1 and 3, these channels being deep enough to receive the legs

50 55

of the staple and being of a width such that the legs of the staple have a sliding fit therein, the channels, however, being so spaced that the head 4 of the staple is clear of the guides and channels. The two legs 1 are connected by a web 10 and the web 10 is spaced from the channels 9 a sufficient distance to allow the head to rotate from a vertical to a horizontal plane, the clearance space in front of the web 10 being designated 11.

The driver 8 has a substantially square end face 12 in the center of which is a rounded depression 13 which, however, is of less width than the over all width of the staple and which provides a camming surface for turning the head of the staple as hereinafter more fully described.

The manner in which the staple is fed into the guide forms no part of the present invention, a complete machine for driving the staple being illustrated in my copending application Serial No. 386,498. It may be stated, however, that the staple is delivered to the driving tool in a plane above the position in which it is shown in Figures 1 and 2 and is moved down to the position shown in Figure 1 where it fits in the channels 9 in the portions 7 of the guide as a preliminary step to the actual driving of the staple. When the staple is to be driven, downward pressure on the driver 8 is exerted against the top edge of the head 4 of the staple. This causes the points of the staple to start to penetrate the material X into which the staple is being driven. At the same time all of the contact between the staple and the driver takes place on the inclined or rounded surface 13. As resistance to the downward movement of the staple increases the surface 13 starts to cam the head 4 to the position shown in Figure 5 and eventually the head is turned to the position shown in Figure 6. When the head of the staple has been turned to the horizontal position the flat part of the driver at each side of the surface 13 also engages the bridge of the staple at points above the top of the legs and continued pressure thereupon drives the staple all the way down. It will be noted that the inwardly offset portions 5 and the decreased width of the head portion 4 enable the head to clear the grooves 9 in the guide so that this part of the staple is free to turn while the legs themselves are confined by the grooves 9 to a vertical plane. The grooves 9 not only serve to hold the legs in one plane while the head is rotating but they serve as a guide for the staple as it is being pushed down by the driver.

From the foregoing it is apparent that I have provided a method of driving tilt-top staples in which the staples have head and leg portions which are initially in the same plane. According to the method one part of the staple is rotated relatively to the other. Also, according to the method, one part of the staple is confined in a plane while the other part is turning. In the method specifically described the turning of the head and the driving of the staple is accomplished with a single downward stroke of the driver but it is obvious that this could be accomplished with a succession of short strokes of the driver or in other ways.

In the modification shown in Figures 9 and 10 the method is substantially the same but the staple is illustrated as being formed of wire. In this case the staple has leg portions 15 at the top of which are inwardly offset shoulders 16. Above the shoulder 16 is a loop-like head portion 17 including a cross bridge 18. In operation the

legs 15 are received in the guides of the stapling chute while the head portion 17, being offset inwardly from the legs, is clear of these guides. Upon pressure being applied to the bridge of the staple through the driver 19 which has camming surfaces 20 the head 17 is turned at right angles to the legs. With a wire staple as shown in these two figures it is unnecessary to provide in the staple chute any clearance space similar to the space 10 because all of the upper part of the staple is bent inwardly whereas in the staple shown in Figure 1 the portion of the head below the extension 5 swings upwardly as the upper part of the head swings downwardly and the clearance space 10 is necessary. The staple shown in Figure 1, however, has a greater holding power when fully driven due to the fact that any force tending to lift one edge of the head of the staple upwardly away from the surface of the material X is resisted by the opposite portion of the head of the staple bearing down against the surface of the said material X.

Also, it is explained in my copending application Serial No. 457,165, that the broad conception of my method contemplates the turning of the legs of the staple while holding the head still as well as turning the head while holding the legs in a plane.

While I have illustrated and described certain specific embodiments of my invention and apparatus for accomplishing the same it will be understood that this is by way of illustration and that various changes and modifications are contemplated within the scope of the following claims.

I claim as my invention:

1. The method of stapling wherein the staple has head and leg portions connected through offset connections which comprises confining one of said portions in a plane and rotating the other in an arc about the offset connections as an axis until one portion is perpendicular to the other, and then driving the staple until the head portion is flat against the work into which the staple is driven.

2. The method of stapling wherein the staples have a head forming portion and a leg forming portion, the head forming portion being of less width than the distance between the leg forming portion, which comprises confining one of said portions in a plane and rotating the other in an arc about an axis of rotation that traverses the head-forming portion until one portion is substantially perpendicular to the other, and then driving the leg-forming portion into the work until the head is substantially flat against the work.

3. In the art of driving staples having tiltable heads and substantially parallel legs pointing in the same direction, the steps which comprise confining the legs in a plane, rotating the head to a position perpendicular to the legs, and then driving the staples until the head is flat against the work.

4. The method of driving a fastener having a head portion and a leg portion disposed in a common plane which comprises initially applying edge pressure to the head portion of the fastener and rotating the head portion to a plane approximately perpendicular to the leg portion during the driving of the staple.

5. The method of driving a fastener having a head portion and a leg portion disposed in a common plane which comprises applying pressure to the edge of the head portion of the staple

and rotating the head by such pressure to a plane approximately ninety degrees from its original plane during the operation of driving the staple and before it has become completely driven.

6. The method of driving a fastener having integral head and leg portions which comprises initially applying the driving pressure to an edge of the head portion, rotating the head portion to a plane approximately perpendicular to the leg portion and completing the driving by 10 pressure in a direction normal to the plane of the head in its last mentioned position.

7. The method of driving a fastener integrally formed from flat sheet metal and which has an enlarged head portion and a leg portion, the 15 leg and head portions being disposed in a com-

mon plane which comprises rotating the head about a transverse axis relatively to the leg to twist the metal at the point of juncture between the head and the leg before the staple has been completely driven and during the operation of driving the same.

8. The method of driving a staple having a head portion and parallel leg portions attached to opposite sides of the head portion which comprises simultaneously driving the staple vertically and with a lateral component of pressure for rotating the head from a plane parallel with the legs to a plane approximately perpendicular thereto with a single blow from a driver.
